CASING SCRAPER

Robbins M. Claypool, Bellaire, and David M. Best, Houston, Tex.; said Best assignor to said Claypool

Application November 22, 1954, Serial No. 470,342

16 Claims. (Cl. 166—173)

The present invention relates to cleaning means and more particularly to scraping type cleaning means for tubular members.

Tubular members, such as pipes, conduits, and the like, over a period of time develop interior conditions which materially impair their efficiency of function or operation. These interior conditions usually are brought about or develop due to the usage to which the member is put, as, for example, the formation of films or caking resulting from greases, synthetic resins, mud or sludge, and cement that may be passed through conduits; or burrs that may be raised within the interior of tubes or the like. It is readily appreciated by those skilled in the art that if such conditions are allowed to develop over a long period of time the tubular member may become totally useless and beyond reclamation by ordinary cleaning methods. Additionally, in the case of tubular members such as conduits that carry semi-liquid substances, the film or cake formed by these substances often becomes extremely hard, which not only creates a serious cleaning problem, but also results in a number of broken or damaged cleaning tools before the cleaning job is satisfactorily accomplished.

Many prior art efforts have been made to devise a rugged, simple cleaning tool capable of coping with the aforescribed cleaning problem, no matter how hard the film or cake has formed within the tubular member. Typical of such prior art efforts and representative of considerable advance in providing an efficient cleaning means for tubular members are United States Letters Patents No. 2,667,930, issued to Dean F. Saurenman, et al., and No. 2,667,931, issued to Reuben C. Baker. A salient feature common to both of the aforescribed cleaners or scrapers is the use of keeper members removably secured to the basic mandrel member by a plurality of screws for holding the scraper elements on the mandrel which serves as the support for the scraper elements.

The present device embodies improved details of construction and function over the Saurenman and Baker patents to provide a rugged, simple, inexpensively manufactured, efficiently functioning tool that solves heretofore deficiencies in prior art tools of the same nature. The tool of the present invention embodies a novel disposition of improved scraper elements for maximum efficient cleaning action, retained on an improved rugged mandrel member in a novel manner by non-removable retention means which eliminates the use of screws and like retention elements which are relatively weak and can easily fail under the severe shear loads imposed thereon during operation. Additionally, the novel non-removable retention means assures a compact assembly that can be easily and quickly assembled or disassembled with maximum ease and efficiency with a minimum opportunity of losing or misplacing a number of small parts, as in prior art devices. The present tool also embodies novel details of construction that not only assure a rugged tool of maximum strength, but also one of simple con-

2

struction readily adapted to inexpensive high speed manufacturing techniques.

It is therefore a primary object of the present invention to provide novel cleaning means.

5 Another object of the present invention is to provide a novel scraping tool.

A further object of the present invention is to provide novel tool means for cleaning the interior of tubular members.

10 A still further object of the present invention is to provide a novel scraping tool with an improved rugged support mandrel.

Yet another object of the present invention is to provide a scraping tool having a plurality of scraping elements novelly disposed to assure maximum cleaning efficiency.

Another object of the present invention is to provide a scraping tool with an improved mandrel novelly mounting non-removable scraper element retention means.

20 Still another object of the present invention is to provide an improved scraping tool with a unique, rugged support mandrel mounting non-removable scraper element retention means, and novel split lock rings.

Yet an additional object of the present invention is to provide an improved scraping tool with a unique rugged support mandrel mounting novel non-removable scraper element retention means that require no screws, rivets, pins, or the like in their assembly.

Still a further object of the present invention is to provide a scraping tool comprising a rugged elongate support mandrel having a plurality of spaced slots serving to mount novel scraper elements retained on the mandrel by novel retention means non-removably mounted on the mandrel and retained in locked position by novel split lock rings.

35 Another object of the present invention is to provide an improved scraping tool for tubular members that is simple, rugged, and inexpensively manufactured, involving a minimum of parts.

40 These and other objects will appear from the following detailed description and appended claims when read in conjunction with the attached drawings, wherein:

Fig. 1 is an elevational view of the completely assembled novel scraping tool of the present invention showing the disposition of the plurality of novel scraping elements;

45 Fig. 2 is an elevational view, partially in section, of the novel support mandrel of the present invention showing the novel mounting slots, grooves, and threaded portions thereon;

50 Fig. 3 is an enlarged exploded perspective view of one of the novel non-threaded end keeper rings of the present invention;

Fig. 4 is an enlarged sectional view of one of the novel threaded inner retention rings of the present novel invention;

55 Fig. 5 is an enlarged exploded perspective view of one of the novel split lock rings of the present invention;

Fig. 6 is an enlarged perspective view of one of the novel left-hand helically toothed scraper elements of the present invention;

60 Fig. 7 is a fragmentary sectional view of one of the novel teeth of the scraper elements of the present invention showing the unique construction thereof.

65 Fig. 8 is an elongated fragmentary sectional view showing the assembly of the scraper elements on the support mandrel and their relation to the novel keeper ring and retention rings and the assembly of the novel split lock ring;

70 Fig. 9 is a sectional view taken substantially along the line 9—9 of Fig. 8;

Fig. 10 is a sectional view taken substantially along the line 10—10 of Fig. 8; and

Fig. 11 is a sectional view taken substantially along the line 11—11 of Fig. 8.

Turning now to the drawing, and particularly to Fig. 1, the novel cleaning tool of the present invention, generally indicated by the numeral 20, will now be particularly described.

Tool 20, as clearly seen in Fig. 1, is an elongate tool which comprises a novel elongate rugged mandrel member generally indicated 22, which serves to mount three spaced groups of scraper elements generally indicated 24, to be more particularly described hereinafter.

Permanently mounted on mandrel 22 adjacent the outermost ends of the upper and lower groups of scraper elements 24, as viewed in Fig. 1, are a pair of non-threaded, non-removable keeper rings 26 which serve to retain the ends of the adjacent groups of scraper elements 24, as will be more particularly described hereinafter. Adjacent the inner ends of the upper and lower groups of scraper elements and the intermediate group of scraper elements are two pairs of novel threaded non-removable retention rings 28 each spaced by intermediate split lock rings 30, which serve to lock the entire assembly. Split lock rings 30 are secured in place by cap screws 32 threadedly engaging each half of split lock rings 30 through aligned threaded openings 34 and 36, as will hereinafter be more particularly described.

It will be readily appreciated from the foregoing brief description of the scraping tool 20 that the tool of the present invention is extremely simple, rugged, and uses no weak securing members, such as screws or the like to carry the extremely high shearing forces imposed on the scraper elements, as in prior art devices.

Turning now to Fig. 2, the novel details of construction of the unique supporting mandrel 22 will now be particularly described.

As clearly seen in Fig. 2, the upper end of mandrel 22 is formed with an integral, externally pipe-threaded portion 38 for connection to pulling means, such as a drill string, for pulling, pushing, or rotating the tool 20 through tubular members to be cleaned. The inner end of portion 38 is integrally connected to enlarged barrel portion 40. The lower end of mandrel 22 is also provided with an elongate, barrel portion 42 having an internally pipe-threaded portion 44, as clearly seen in Fig. 2, for connection to operating means (not shown). The inner ends of barrel portions 40 and 42 are integrally connected to enlarged cylindrical shoulder portions 46 and 48, respectively, by means of conical connecting chamfer portions 50 and 52, respectively. Intermediate cylindrical shoulders 46 and 48 are three spaced enlarged integral bosses, generally indicated at 54, of the same diameter as the diameter of cylindrical shoulders 46 and 48. Smooth bottomed peripheral keeper ring grooves 56 are disposed intermediate shoulders 46 and 48 and the adjacent bosses 54, while intermediate adjacent pairs of bosses 54 is a peripherally grooved portion generally indicated by the reference numeral 58 and comprising two threaded portions 60 adjacent each of the bosses 54 and spaced from each other by intermediate smooth bottomed peripheral groove 62 having a slightly greater depth than the threads on portions 60. Each of the bosses 54 is provided with four equally spaced axially extending flat-bottomed slots 64, which extend partially into the adjacent grooves 56 or threaded portions 60 and terminate in a gradual slope upwardly at the peripheral surface of the adjacent grooves or threaded portions, as indicated at 66, for a purpose which will hereinafter appear. The slots 64 of each boss are offset 30° with respect to the slots on an adjacent boss 54 so that scraper elements 24 will overlap each other in their scraping action to assure 100% cleaning action by the scraper elements within the tubular member to be

cleaned, as will hereinafter be more particularly described.

As fragmentarily shown in Fig. 2, an axially extending opening 55 extends through the entire length of mandrel 22 to permit circulation. A fluid such as water may be passed through the mandrel 22 into the interior of the tubular member being cleaned or scraped for purposes of lubrication and flushing of the loosened scrapings therein, as is well known in the art.

Turning now to Figs. 3 through 6 in conjunction with Fig. 8, the details of the novel keeper rings, retention rings, split lock rings and scraper elements and their mounting on support mandrel 22 will now be particularly described.

As shown in Fig. 3 non-threaded keeper rings 26 are plain cylindrical rings having smooth internal and external surfaces 68 and 70 and having a thickness equal to the depth of grooves 56.

After being formed, keeper rings 26 are split on a 20 diameter to form a pair of semi-circular rings 72 and 74 for purposes of assembly which will appear hereinafter. The semi-circular portions 72 and 74 are placed around mandrel 22 with their internal surfaces 68 in contact with the bottom of grooves 56 and with their sides 76 and 78 25 in contact with the adjacent sides of cylindrical shoulders 46 and 48 and bosses 54, respectively. The ends 80 and 82 of the semi-circular portions 72 and 74, respectively of rings 26 are in abutting contact in their assembled position. Once semi-circular portions 72 and 74 have 30 been properly placed on mandrel 22, they are welded to each other along abutting ends 80 and 82, to form a complete integral ring again, and also to mandrel 22 along shoulders 46 and 48 and the adjacent ends of bosses 54 35 between the slots and the adjacent side of ring 26, as indicated at 84 and 85, respectively, in Figs. 1 and 8. Thus, once ring 26 is completely assembled on mandrel 22, it forms an integral part thereof and also forms a simple rugged keeper means for the adjacent scraper elements 24 as will hereinafter appear. Attention is also 40 called to Fig. 8 wherein it is clearly seen that slots 64 in end bosses 54 extend under rings 26 for a purpose to be described.

Turning now to Fig. 4, the details of the novel threaded retention rings 28 will now be particularly described. 45 These retention rings are initially formed as a full ring and then cut to form two halves as shown in Fig. 3. As clearly seen in Fig. 4, retention rings 28 are provided with a smooth external surface 86 having a diameter equal to the diameter of bosses 54, and a threaded inside surface 88 for mutual threaded engagement with threaded portions 60 of mandrel 22. Extending inwardly from one side of retention rings 28 is a smooth counterbore 90 equal in diameter to the depth of threads 88 and equal in axial length to the portion of slots 64 extending into 50 threaded portion 60 for purposes of overlying and retaining scraper elements 24, as will hereinafter appear. The two halves of threaded retention rings 28 are assembled on threaded portion 60 and are welded to each other or 55 together along adjacent abutting edges to form integral retention rings 28 non-removably threadably adjustably mounted on mandrel 22, somewhat similar to the manner of mounting keeper rings 26. The axial length of retention rings 28 is exactly the same as the axial length of 60 threaded portions 60, for a purpose which will hereinafter be more particularly described.

In Fig. 5 there are shown the details of novel split lock rings 30 which comprise halves 94 and 96, each having smooth inside and outside surfaces 98 and 100, respectively, the diameters of which are substantially equal to 70 the diameters of slots 62 and bosses 54, respectively, for a purpose which will appear. Halves 94 and 96 of lock rings 30 abut along faces 102 in their assembled positions and are each provided with diametrically opposed pairs of threaded apertures 34 and 36 as heretofore described which are in alignment in their assembled posi-

tion for the reception of a pair of securing cap screws 32, which fixedly join halves 94 and 95. The axial length of lock rings 30 is equal to the width of slots 62.

Novel scraper elements 24 are generally rectangular blocks, as clearly seen in Fig. 6, having a main body portion 104 surmounted by integral square type left-hand helically cut teeth 106 and having integral end tongues 108. The upper surfaces 110 of tongues 108 are curved to conform to the curvature of the retention rings while the lower surfaces 112 of each of the entire scraper elements 24 are flat, as seen in Fig. 6, to conform to the flat bottom of slots 64 of mandrel 22. As shown in Fig. 7, the longitudinal sides of teeth 106 are cut away along the lines 113—113, and a very hard composition, indicated at 114, such as stellite or other composition combinations like the cobalt-chromium-tungsten alloys, is affixed by suitable means, in place of the removed material, to provide a keen abrasive resistant scraping edge for maximum operating efficiency and extended service life. The undersides of scraper elements 24 are provided with three equally spaced blind apertures 116, as best seen in Fig. 8, for the reception of biasing means as will be hereinafter described.

Turning now to Fig. 8, the novel manner of assembling the scraper elements on mandrel 22 will now be particularly described. As heretofore described, non-threaded keeper ring halves 72 and 74 are assembled into grooves 56 of mandrel 22 and are then welded to each other along abutting edges 80 and 82 and to mandrel 22 along joint or junctures 84 and 85, as heretofore described. All of the threaded retention rings 28 are similarly assembled on mandrel 22 to form retention means that are non-removable from but adjustable axially on the mandrel. With reference to Fig. 8, lock ring 30 is not assembled on mandrel 22 and the leftmost retention ring 28 is unthreaded or moved to the right away from its adjacent boss 54 exposing the portion 66 of slot 64 which extends into threaded portion 68. Springs 118 are mounted in blind apertures 116 on the underside of scraper elements 24, and four of the scraper elements are mounted on mandrel 22 by slipping end tongues 108 into slot portions 66 beneath keeper ring 26. The four scraper elements in this group are then all pressed into slots 64 toward mandrel 22 compressing springs 118, and leftmost threaded retention ring 28 is threaded toward its adjacent boss 54 until it abuts the end of its boss 54, so that counterbored portion 90 of retention ring 28 overlies the right-hand tongues 108 of scraper elements 24. The axial length of body portion 104 of the scraper elements is slightly less than the axial length of boss 54 so that the ends of keeper ring 26 and retention ring 28 will not bind the scraper elements 24, and they thus will be freely biased outwardly by springs 118.

Turning now to Figs. 1 and 2, one method of assembling the middle group of scraper elements will now be described, remembering that split lock rings 30 are not in their assembled positions. The two retention rings 28 adjacent to opposite sides of the intermediate boss 54 may be threaded and thus capable of being moved away from boss 54, exposing end portions 66 of slots 64. Four scraper elements 24 with their springs 118 are then mounted in slots 64 with their end tongues 108 extending into portions 66 of slots 64. The two retention rings 28 are then threaded back toward middle boss 54 until the adjacent ends of retention rings 28 abut the adjacent sides of middle boss 54. In this position the counterbores 90 will completely overlie tongues 108 and will retain scraper elements 24 in slots 64 against the biasing force of springs 118. It will also be emphasized here that retention rings 28 abut the adjacent sides of boss 54 while the axial length of body portion 104 of scraper elements is slightly less than the length of boss 54 to permit free action of scraper elements 24 in slots 64 under the biasing force of springs 118 for maximum freedom of action and operation.

A preferable method of assembling the middle group

or intermediate set of scraper elements 24 will now be described. Only one of the retention rings 28 adjacent the intermediate boss 54 is threaded away from this boss exposing circumferentially spaced end portions 66 of slots 64, while the other retention ring 28 remains in position against the other side of boss 54 in overlying relation to the other end portions 66 of slots 64. Scraper elements 24, with their associated springs in place, are then placed in slots 64 and their end tongues 108 are slipped under the retention ring that has not been threaded away from boss 54. Scraper elements 24 are then all pressed into slots 64 compressing springs 118, and the other retention ring 28 is then threaded moved into abutting relation with its adjacent end of boss 54 to overlie the adjacent tongues 108 of scraper elements 24. It will readily be appreciated that no matter what method of assembly is employed the scraper elements are easily assembled with a minimum amount of effort and adjustment.

The lower group of scraper elements 24, as viewed in Fig. 1, are assembled in the same manner in which the group of scraper elements described in connection with Fig. 8 were assembled. Once all of the scraper elements 24 have been assembled and all the retention rings have been threaded into abutting engagement with their adjacent bosses 54, the split lock rings 30 are interposed between pairs of retention rings 28 and threaded connected together by means of recessed head cap screws 32 to completely lock the assembly in a compact rugged unit.

It will be readily appreciated from the foregoing detailed description of the novel cleaning tool of the present invention that it is of relatively simple rugged construction and that the relatively high shear forces imposed on the scraper element are not carried by a plurality of relatively weak screws, rivets, or pins as in prior art devices, but are carried by relatively large rugged keeper or retention rings in pushing and pulling action and by the sides of bosses 54 in rotation which are capable of carrying such loads with little ill effect.

It frequently happens that it is necessary or desirable to rotate the tool as distinguished from pushing or pulling the same, and since the teeth 106 are of a curved formation, such rotation provides an excellent cutting action. In addition to the fact that the tool will cut very well, it will be noted that the parts are so assembled that a rugged construction results which is not prone to become disassembled in use. Rotative force is transmitted from the drill string or the like down into the mandrel and then from the inner face of the slot 64 in the bosses 54 directly to the rather lengthy sides of the scraper blocks generally indicated at 24. The retention rings furnish the drive when going in or coming out of the hole; that is, when pushing or pulling, but the sides of the slots 64 drive the scraper elements while rotating, as rotation is frequently employed, since this permits two operations at one time. For example, it frequently happens that a bit is connected to the lower threaded end 44 of the mandrel and scraping operations are carried on simultaneously with the drilling of a cement plug in the casing.

Further, it will be readily appreciated that the novel mandrel 22, the keeper, retention rings, lock rings, and the novel scraper elements are all formed by means of simple lathe and milling operations which result in a simple rugged tool that is easily manufactured by means of high speed inexpensive manufacturing methods.

The present invention may be embodied in other specific forms without departing from the spirit or essential scope or characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be included therein.

We claim:

1. In a casing scraper, an elongate support member, connecting means on said elongate support member for attachment to a pipe string, a plurality of slots in said support member for removably receiving a plurality of scraper elements, a plurality of scraper elements, for scraping the inner walls of tubular members, removably mounted in said slots, and a plurality of pairs of retention means non-removably mounted on said member and each of said pairs being cooperative with the adjacent ends of said scraper elements for fixedly securing said scraper elements in mounted position on said support member.

2. In a casing scraper, an elongate support member, integral connecting means on said support member for attachment to a pipe string, a plurality of axially extending slots in said support member for mounting a plurality of scraper elements, a plurality of scraper elements resiliently removably mounted in said slots on said elongate support member, and pairs of retention means non-removably mounted on said support member partially overlying adjacent ends of said scraper elements and cooperative with said scraper elements for securing said scraper elements in their mounted position on said support member.

3. A casing scraper assembly comprising an elongate support member, connecting means on said elongate support member for attachment to a pipe string, a plurality of scraper elements mounted on said support member, a plurality of pairs of retention means non-removably mounted on said support member in encircling relation to said support member and in partial overlying relation to the adjacent ends of said scraper elements to retain the scraper elements on said support member, and multiple lock means mounted in encircling relation to said support member and cooperative with any two adjacent retention means to lock said scraper assembly against longitudinal movement in a firm assembled relation.

4. The device as set forth in claim 3 wherein biasing means are operatively interposed between said support member and said scraper elements.

5. A casing scraper assembly comprising an elongate, hollow support member, a plurality of scraper elements mounted on said support member, a plurality of pairs of retention means non-removably mounted on said support member in encircling relation thereto and in partial overlying relation to the adjacent ends of said scraper elements to cooperate with said support member in retaining said scraper elements in assembled position, split lock means mounted in encircling relation to said support member and cooperative with at least some of said retention means to maintain said retention means in scraper element retaining position, and securing means fixedly securing said split lock means together to securely lock said scraper assembly in firm assembled relation.

6. A casing scraper assembly comprising an elongate support member, a plurality of axially extending slots in said support member for mounting a plurality of scraper elements, a plurality of scraper elements removably resiliently mounted in said slots on said elongate support member, a plurality of pairs of annular retention means non-removably mounted on said support member partially overlapping the adjacent ends of said scraper elements and cooperative with said slots for securing said scraper elements in their mounted position on said support member, and lock means cooperative with at least some of said retention means to lock said scraper assembly in firm assembled relation.

7. A casing scraper assembly comprising an elongate support member, a fluid passage extending through said support member, spaced shoulders on said support member, a plurality of axially extending slots in said support member intermediate said shoulders for mounting a plurality of scraper elements, a plurality of scraper elements removably resiliently mounted in said slots on said elongate support member, pairs of annular retention means non-removably mounted on said support member partially overlapping the adjacent ends of said scraper elements and cooperative with said slots and shoulders for securing said scraper elements in their mounted position on said support member, and lock means cooperative with at least some of said retention means to lock said scraper assembly in firm assembled relation.

gate support member, pairs of annular retention means non-removably mounted on said support member partially overlapping the adjacent ends of said scraper elements and cooperative with said slots and shoulders for securing said scraper elements in their mounted position on said support member, and lock means cooperative with at least some of said retention means to lock said scraper assembly in firm assembled relation.

8. A casing scraper assembly comprising an elongate support member, integral connecting means on said support member for attachment to a pipe string, spaced shoulders on said support member, a plurality of axially extending slots in said support member intermediate said shoulders for mounting a plurality of scraper elements, a plurality of scraper elements removably resiliently mounted in said slots on said elongate support member, a plurality of annular first retention means permanently fixedly mounted on said support member, a plurality of annular second retention means non-removably adjustably mounted on said support member, said first and second retention means partially overlapping said scraper elements and cooperative with said slots for securing said scraper elements in their mounted position on said support member, and lock means cooperative with said second retention means to lock said scraper assembly in firm assembled relation.

9. A casing scraper assembly comprising an elongate support member, an axially extending fluid passage therethrough, integral connecting means on said support member for attachment to a pipe string, spaced circumferential shoulders on said support member, a plurality of axially extending slots in said support member intermediate said shoulders for mounting a plurality of scraper elements, a plurality of scraper elements resiliently removably mounted in said slots on said elongate support member, a plurality of first circumferential retention means permanently fixedly mounted on said support member, a plurality of second circumferential retention means non-removably adjustably mounted on said support member, a pair of said first and second retention means partially overlapping each of said scraper elements and cooperative with said slots for securing said scraper elements in their mounted position on said support member, and lock means cooperative with said second retention means to lock said scraper assembly in firm assembled relation.

10. A casing scraper assembly comprising an elongate support member, integral connecting means on said support member for attachment to a pipe string, spaced shoulders on said support member, a plurality of axially extending circumferentially and axially spaced mounting slots for mounting a plurality of scraper elements, a plurality of scraper elements mounted in said slots on said support member, a plurality of annular first retention means permanently fixedly secured on said support member, a plurality of annular second retention means non-removably adjustably mounted on said support member, a pair of said first and second retention means partially overlapping each of said scraper elements and cooperative with said slots for securing said scraper elements in their mounted position, and lock means cooperative with said second retention means to lock said scraper assembly in firm assembled relation.

11. The device as set forth in claim 10 wherein spring means are operatively interposed between the underside of said scraper elements and the bottom of said slots to resiliently mount said scraper elements.

12. A casing scraper assembly comprising an elongate support member, integral connecting means on said support means for attachment to a pipe string, spaced circumferential shoulders on said support member, a plurality of axially extending circumferentially spaced mounting slots intermediate said shoulders for mounting a plurality of scraper elements on said support member, a

plurality of scraper elements removably resiliently mounted in said slots, a plurality of first circumferential retention means permanently fixedly mounted on said support member, a plurality of second circumferential retention means non-removably adjustably mounted on said support member, a pair of said first and second retention means partially overlapping each of said scraper elements and cooperative with said slots for securing said scraper elements in their mounted position on said support member, and lock means cooperative with said second retention means to lock said scraper assembly in firm assembled relation.

13. A casing scraper assembly comprising an elongate support member, integral connecting means on said support member for attachment to a pipe string, spaced circumferential shoulders on said support member, spaced bosses on said support member intermediate said shoulders, a plurality of axially extending circumferentially spaced slots in said bosses for mounting a plurality of scraper elements on said support member, a plurality of scraper elements removably resiliently mounted in said slots, a plurality of first circumferential retention means permanently fixedly mounted on said support member, a plurality of second circumferential retention means non-removably adjustably mounted on said support member, a pair of said first and second retention means partially overlapping each of said scraper elements and cooperative with said bosses to retain said scraper elements in their assembled position, and lock means cooperative with said second retention means to lock said scraper assembly in firm assembled relation.

14. A casing scraper assembly comprising an elongate support member, integral connecting means on said support member for attachment to a pipe string, spaced circumferential shoulders on said support member, a plurality of spaced bosses on said support member intermediate said shoulders, a plurality of axially extending circumferentially spaced slots on said bosses for mounting a plurality of scraper elements, a plurality of scraper elements resiliently removably mounted in said slots having toothed scraping surfaces with hard abrasive resistant auxiliary material attached to said teeth, a plurality of annular first retention means permanently fixedly mounted intermediate said shoulders and adjacent said bosses, a plurality of annular second retention means non-removably and initially adjustably mounted intermediate successive bosses, a pair of said first and second retention means partially overlapping each of said scraper elements and cooperative with said bosses for retaining said scraper elements in assembled position, and lock means mounted to lock said scraper assembly in firm assembled relation.

15. A casing scraper assembly comprising an elongate support member, spaced circumferential shoulders on said support member, a plurality of axially spaced bosses on said support member intermediate said shoulders, cir-

cumferential grooves intermediate said shoulders and the adjacent bosses, threaded portions intermediately disposed between mutually adjacent bosses, second circumferential grooves dividing said threaded portions, axially extending circumferentially spaced slots in said bosses, a plurality of scraper elements resiliently removably mounted in said slots, scraping teeth on said scraping elements having auxiliary material fixedly attached to the sides of the teeth for maximum abrasion resistance, a plurality of annular first retention means permanently fixedly mounted in said first grooves and partially overlapping some of said scraper elements, a plurality of annular second retention means non-removably and initially adjustably mounted on said threaded portions and also partially overlapping the scraper elements to retain them in said slots, and lock means mounted in said second grooves to maintain said second adjustably mounted, retention means in adjusted non-removable retaining position to maintain said scraper elements in firm assembled relation.

16. A casing scraper assembly comprising an elongate support member, spaced circumferential shoulders on said support member, a plurality of axially spaced bosses on said support member intermediate said shoulders, circumferential grooves intermediate said shoulders and adjacent bosses, threaded portions intermediately disposed between mutually adjacent bosses, second circumferential grooves dividing said threaded portions, axially extending circumferentially spaced slots in said bosses, a plurality of scraper elements resiliently removably mounted in said slots, tongue means on opposite ends of said scraper elements, scraping teeth on an outer surface of said scraper elements having auxiliary extremely hard material affixed to the sides thereof to provide abrasion resistant scraping edges, a plurality of first retention rings permanently fixedly mounted in said first grooves in encircling relation to said support member and in overlapping relation to the adjacent tongue means of adjacent scraping elements, a plurality of second retention rings non-removably threadably mounted on said threaded portions and in overlapping relation to the adjacent tongue means of adjacent scraping elements, split lock rings mounted in said second grooves to maintain said second retention rings in adjusted retaining position, and securing means fixedly securing the portions of said split lock rings together to lock said scraping assembly in firm assembled relation.
